Primary Examiner — Clare E Heflin(74) *Attorney, Agent, or Firm* — Michael Best & Friedrich LLP(57) **CLAIM**

The ornamental design for a performance high-bay luminaire, as shown and described.

DESCRIPTION

FIG. 1 is a bottom perspective view of an embodiment of the design;

FIG. 2 is a top perspective view of FIG. 1;

FIG. 3 is a right side view of FIG. 1 with the other side being a mirror image thereof;

FIG. 4 is a front side view of FIG. 1 with the rear view being a mirror image thereof;

FIG. 5 is a top view of FIG. 1; and,

FIG. 6 is a bottom view of FIG. 1.

The broken lines show portions of the performance high-bay luminaire that form no part of the claimed design.

1 Claim, 6 Drawing Sheets(56)
